 corporation of New Jersey

Application October 23, 1948, Serial No. 56,227

15 Claims. (Cl. 174—22)

1

This invention relates to high tension electric cables of the type in which insulated conductors are loosely enclosed by a pipe which is filled with an insulating fluid under pressure. Usually the pipe is a rigid pipe into which one or several insulated conductors have been drawn, and the insulating fluid usually is an oil or an inert gas such as nitrogen. Such cables are the subject of the Sonnenfeld Patent 2,250,239.

More particularly, the invention relates to means for anchoring the insulated conductors against movement in the pipe at desired locations, such movement resulting from expansion and contraction of the conductors caused by variations in temperature during operation of the cable. This problem is of prime importance at semi-stops in the pipe, in which each insulated conductor, usually at a point near its connection to another insulated conductor, passes through an opening in a barrier plate across the pipe and is engaged by a packing gland or the like. The packing gland closes the opening around the insulated conductor and compresses the conductor insulation around its entire circumference. The purpose of this arrangement is to restrict movement of the insulating fluid longitudinally along the pipe substantially to the amount which migrates through the compressed conductor installation where the conductors pass through the barrier plate.

It is an object of the invention to provide improved means for securing an insulated conductor against longitudinal movement at desired locations in the pipe under all operating conditions, and for doing this without damage to the conductor insulation. It is an object of the invention to provide improved means for anchoring the cable conductors at a semi-stop without the necessity of applying pressure on the insulation under the packing gland sufficient to hold the conductor against movement or to damage the insulation. It is a further object of the invention to provide improved joints for cables of the type described. Other objects and advantages of the invention will appear hereinafter.

A preferred embodiment of the invention has been selected for purposes of illustration and description and is shown in the accompanying drawings, wherein:

Figure 1 shows end portions of two lengths of pipe type cable and a semi-stop joint therefor, part of the joint casing being broken away to disclose the construction;

Figure 2 is a view to enlarged scale of the left-hand portion of Figure 1, showing details of the semi-stop construction more clearly;

2

Figure 3 is a view to enlarged scale of the left-hand portion of Figure 1, showing details of the means for anchoring the conductors against movement;

5 Figure 4 is a transverse section to enlarged scale through the cable joint substantially on the line 4—4 of Figure 1; and

10 Figure 5 is a transverse section to enlarged scale through the cable joint substantially on line 5—5 of Figure 1.

The same reference numerals are used throughout the figures to designate the same parts.

In cables of the type described, variations in the length of the insulated conductors resulting from changes in the cable temperature produce forces in the insulated conductors tending to cause relative longitudinal movement between the conductors and the pipe. The conductors are loosely enclosed by the pipe and ordinarily 15 are free to snake within the pipe, except as they may be restrained by contact with other conductors in the pipe. The insulated conductors are not very flexible, and are drawn into the pipe in long lengths, usually more than a thousand 20 feet. Where several conductors are enclosed within a single pipe, as is usually the case, their relative positions in the pipe may vary along its length and therefore they will not all have the same freedom of movement. For these and 25 other reasons, the forces set up in the conductors will not be distributed uniformly in the several conductors, or uniformly throughout the length of any particular conductor and at any point along the cable the force tending to move 30 a conductor longitudinally as the cable temperature changes may amount to many hundreds of pounds. The maximum forces may occur upon 35 contraction of the conductor if cooled considerably below the temperature at the time of installation.

40 The forces set up in the conductors on expansion are largely limited by the snaking of the conductors within the pipe, but in some places this transverse movement of the conductors with-

45 in the pipe, in the absence of any holding means, may be accompanied by slight movement of the conductors longitudinally of the pipe. The forces set up on contraction result in straightening and tensioning the conductors. Throughout much of 50 the length of the cable this slight longitudinal movement of the conductors within the pipe probably is of no particular consequence, but if it occurs at a location where it is desired to hold the insulated conductors against movement, it is likely to result in serious damage to the conductor insulation, or in damage to the holding means.

Joints in cables of the type described usually are semi-stop joints, that is, joints in which the flow of the insulating fluid from one of the pipe lengths to the connected pipe length is restricted to a small amount. This requires a barrier of some sort in the pipe with fluid-tight seals to the pipe wall and to the insulated conductor or conductors. In order to avoid damage to the seals and to the conductor insulation it is desirable that there be no relative movement between the insulated conductors and the pipe at such a semi-stop joint.

A semi-stop in a pipe type cable usually, although not necessarily, is located at a cable joint. In the usual semi-stop the insulated conductors pass through fairly close fitting openings in a barrier plate extending across the pipe with its edge rigidly connected fluid tight relative to the pipe. No particular problem is encountered in providing a seal between the barrier plate and the pipe, or in securing the barrier plate against movement relative to the pipe. The insulated conductors are engaged by packing glands where they pass through the openings in the barrier plates and stuffing boxes or the like are provided for compressing the packing glands about the insulated conductors. Each packing gland compresses the conductor insulation to some extent around its entire circumference, and serves not only to seal the opening through the barrier plate around the insulated conductor, but also to restrict the flow of insulating fluid longitudinally through the conductor insulation under the gland.

In cables of the type described, the conductors customarily are individually insulated with a multiplicity of over-lying helical wrappings of paper tape. Only a small force is required to slide the paper insulation on the conductor in the absence of externally produced pressure of the insulation against the conductor. If the conductor is to be held against movement, the pressure of the holding means must be of such magnitude and applied to the insulated conductor in such a manner as to prevent slipping between the over-lying layers of the paper insulation and also between the paper and the conductor.

Prior to the present invention, the packing gland of the semi-stop above described has been relied upon to hold the insulated conductor against movement. This has required increasing the pressure of the packing gland on the exterior of the conductor insulation until the inner surface of the insulation gripped the conductor with sufficient pressure to hold it against the forces tending to move the conductor. This has meant pressures on the insulation far beyond anything required merely to restrict the flow of the fluid insulation through the barrier plate opening to an acceptable amount, and the conductor insulation has been seriously weakened.

For such a device to produce pressure on the conductor under the insulation, the entire mass of insulation must be compressed. Since the paper of the insulation is not elastic beyond an insignificant amount, the resulting gland pressure applied around the entire circumference of the insulated conductor produces sharp longitudinal creases in the paper by which the circumference of any layer of paper adjusts itself to the smaller diameter to which it is compressed. These deep creases extend throughout the insulation on the conductor. Of course, such gland pressure cannot readily be applied over more than a very short length of the cable, so that aside from the question of damage to the insu-

lation there are definite limitations on the ability of the circumferential holding device to restrain the cable longitudinally. For the reasons mentioned, the gland method is far from satisfactory for producing pressure on the conductor which will prevent slipping of the conductor under the insulation.

According to the present invention, clamping means are provided for gripping the insulated conductors firmly and without impairment of the electrical insulation. This clamping means can be easily anchored to the pipe line to prevent movement between the insulated conductors and the pipe. When used in a semi-stop joint, this clamping means may be applied either to the body of insulation built up over the connected conductor ends, or to the factory applied insulation on one of the conductors adjacent the joint, or to both, and the clamping means may be anchored to the barrier plate. In such a joint the packing gland is not called on to play any part in holding the insulated conductor against longitudinal movement, and therefore the pressure of the packing gland on the conductor insulation need be sufficient only to restrict the flow of insulating fluid through the opening around the conductor to an acceptable figure.

The present invention will now be described particularly with reference to a semi-stop joint but it will be understood that the means for securing an insulated conductor against movement in the cable pipe is not limited to use at the cable joints.

Referring first to Figure 1 of the drawings, pipes 11 and 12, enclosing insulated conductors 13 and 14, respectively, are connected in end to end relation by means of the joint casing 15 and the adapters 16 and 17. Ordinarily the pipes, adapters and joint casing will be made of steel, and the connections therebetween will be welded to insure a fluid tight and a mechanically strong connection.

Within the joint casing, near the ends thereof, are the barrier plates 18 and 19, which are made, for example, of bronze, and which cover the larger ends of the adapters 16 and 17 respectively. The barrier plates are secured tightly against the ends of the adapters, as by means of cap screws 20 which pass through holes spaced around and near the edges of the barrier plates and engage threaded holes in the ends of the adapters. Gaskets between the barrier plates and the adapters insure fluid tight connections.

The ends of the insulated conductors 13, of which there are three in the illustrative embodiment, contained within the pipe 11 passed through symmetrically spaced openings in the barrier plate 18 into the joint casing 15. These openings in the barrier plate are slightly larger than the insulated conductors so as to permit threading the insulated conductors through the openings. Skid wires 22 applied over the insulated conductors at the factory to decrease the friction and to protect the insulation against damage while the conductors are being pulled into the pipe are suitably terminated short of the barrier plate, as shown.

Surrounding each insulated conductor 13 adjacent the barrier plate 18 is a packing gland 23, including gaskets, sleeve, follower, and means associated with the barrier plate for compressing the packing gland against the barrier plate and also against the conductor insulation around its entire circumference. Merely for clarity in the drawings the packing glands are omitted in

Figure 1, but are shown in Figure 2, which is an enlarged view of the left-hand portion of Figure 1. In the illustrative embodiment, tightening the nuts on the studs 25, which are mounted in the barrier plate 18, will cause the follower 26, to compress the gland gaskets against the barrier plate and against the conductor insulation. Thus, the packing glands will seal the openings in the barrier plate exteriorly of the insulated conductors 13 and, by reason of the pressure applied on the conductor insulation, will restrict the flow of insulating fluid longitudinally through the conductor insulation under the gland.

The pressure exerted by the packing gland on the conductor insulation should be sufficient to hold back the pressure of the insulating fluid and to restrict the flow of insulating fluid longitudinally through the conductor insulation to an acceptable figure. Desirably this pressure should be several times the hydrostatic pressure being held back. Such a pressure on the conductor insulation may cause some creasing in the outer paper layers, perhaps to about one-half the depth of the insulation, but will not unduly weaken the insulation. For example, with a pressure on the fluid insulation contained within the cable of about 250 pounds per square inch, the pressure exerted by the packing gland on the insulation might be of the order of 1000 pounds per square inch. A still higher pressure is required to buckle the entire thickness of insulation of well-made paper insulated cable and only with such a buckling can the cable conductor be held firmly by the packing gland against slipping within the insulation.

While the barrier plate 19 at the other end of the joint casing might be omitted in some cases, ordinarily it is employed in a manner similar to the barrier plate 18 for the purpose of restricting the flow of insulating fluid between the pipe 12 and the joint casing 15. The ends of the insulated conductors 14 contained within the pipe 12 pass through symmetrically arranged and fairly close fitting openings in the barrier plate 19 into the joint casing 15. The skid wires 22 on the conductors 14 are terminated short of the barrier plate and each insulated conductor is surrounded by a packing gland 23 similar to those employed with the conductors 13 where they pass through the barrier plate 18.

Within the joint casing 15, the ends of corresponding conductors 13 and 14 are connected together and insulated in known manner. The insulation applied over each conductor joint may be built up to a somewhat larger diameter than the factory applied insulation on the conductor, although this is not necessarily so. The built-up insulation may be cylindrical in form for a distance and then taper down at both ends to the original conductor insulation, and such a construction is shown in the illustrative embodiment. Ordinarily the insulated conductors 13 and 14 will be shielded, and a shielding layer will be applied over the joint insulation between the shields on the two connected conductors.

According to the present invention, the insulated and shielded conductors are firmly gripped within the joint casing by an arrangement which grips the insulated conductors along narrow zones extending longitudinally of the conductors and spaced circumferentially around the conductors. The insulated conductor is gripped by a plurality of longitudinally extending strips, sometimes referred to hereinafter as "strip grips,"

which are pressed against the conductor insulation by enclosing clamping means.

The number of strip grips employed for holding each insulated conductor may vary, but there always will be at least two, and usually three or four. While the number used may be greater than four, there is comparatively little gain in gripping effect by the use of a larger number, and the gripping arrangement will be more difficult to manufacture and install. The strip grips desirably should be narrower than the spaces separating them, and their length, desirably not less than about three times their width, may be many times greater than the width. The strip grips may grip the conductors over the factory applied insulation on the conductors, or over an insulated conductor joint, whether of the same diameter as the factory applied insulation or of larger diameter, or over both.

In the illustrative embodiment there are four strip grips 27 spaced uniformly around each insulated conductor. The distance between the strip grips, measured along the outer surface of the insulated and shielded conductor, is about one and one-half times the width of a strip grip. The strip grips 27 are applied over the insulation, which has been built up over the conductor joint to a somewhat larger diameter than the original factory insulation, and extend for approximately the full length of the joint insulation. The edges of the joint insulation hidden by the strip grips in Figure 1 are shown in broken lines. The joint insulation tapers down at its ends to the factory applied insulation on the conductors, and wedge shaped insulating pieces 28 over these tapered portions build up the diameter under the strip grips to approximately the diameter at the central part of the insulated joint. These wedge shaped insulating pieces will be held in place against the tapered end portions of the built-up insulation by the pressure of the over-lying strip grips.

The strip grips desirably are made of non-magnetic material, for example copper. While metal is preferred because of its strength, the strip grips may be made from strong insulating material, provided it does not contain any water. If the strip grips are made of metal, as in the illustrative embodiment, they preferably should be enclosed by thin insulating layers, for example a helical wrapping of paper tape over each strip grip. Thin insulating strips 32 may also be employed between the strip grips and the enclosing clamps to further insulate these parts from each other. While it may be desirable to have all of the strip grips and their clamping means grounded, the purpose of the insulating coverings on the strip grips is to prevent electrical contact therebetween at undesired locations. In this way, it will be possible to keep the losses from circulating currents which may be induced in the metallic parts of the gripping arrangement to a low figure.

The strip grips 27 spaced circumferentially around each insulated conductor are pressed and held firmly and resiliently against the insulated conductor by suitable clamping means. In the illustrative embodiment, a plurality of ring shaped metal clamps 29 are spaced longitudinally along each insulated conductor exteriorly of the strip grips. The clamps 29 are provided with radially disposed set screws 30 bearing against at least some of the strip grips to press them against the insulated conductor.

These clamps 29 should contain a certain

amount of springiness, so that they will be able to follow up some relaxation of the insulation on which the strips bear. They must be of sufficient strength so that they will contain stresses of the nature of bending moment and yet must be sufficiently flexible so that there will be some bending, that is, some distortion of the rings as contrasted to simple tensile forces which would occur if the portions of the rings between the strip grips were simply plane surfaces.

As illustrated, the clamps 29 are substantially circular in form and should be sufficiently elastic to permit increase of the diameter at the thrust bearings by a few thirty seconds of an inch without permanent distortion, and to produce at the same time a thrust against the strips of the required pressure to hold the conductor. Or, in other words, the ring clamps should be sufficiently elastic so that upon tightening the set screws 30 there will be an increase of several percent in the diameter of the ring clamps along the axis of the set screws without permanent distortion of the clamps. Desirably this increase will be of the order of three percent or more.

In order to obtain uniform distortion of the cable insulation it would be desirable for each ring clamp to have a set screw for each strip grip, and for the set screws all to be brought up to tension successively by small increments. In a multiple conductor cable it is difficult to use more than two set screws in a ring clamp because of inaccessibility and, accordingly, the desired arrangement involves the use of only two set screws. However, it is difficult to obtain symmetrical distortion of the insulation with only the two set screws per clamp and it may be desirable to tighten the strip grips initially by the use of temporary tightening means, for example, C clamps placed adjacent to the rings, two C clamps for each ring. When these C clamps are tightened up successively by small increments, the resulting distortion of the insulation is substantially uniform, or, stated in another way, the distorted insulation is symmetrical about a plane passing through the center of either pair of opposing strips. After the strips have been brought into position with the required force by means of the C clamps, the set screws 30 are then tightened and the C clamps removed.

By reference to Figure 4 of the drawings, it will be seen that, when four strip grips are used, the conductor insulation becomes more or less square with rounded corners, in cross-section. If the ring clamps are placed in position first by tightening the two set screws, there tends to be a greater amount of bulging of the insulation in one quadrant or one semi-circle of the insulated conductor than in the remaining portions. This would mean that for a given amount of compression there would be a greater distortion of the insulation than will be obtained where the bulging is divided evenly between the four quadrants.

The strip grip can produce a high pressure per unit length of the insulated conductor without increasing the paper, because the distortion which it produces is confined to a slight bending of the paper between the strip grips, which does not damage the paper. Not only is there a lack of mechanical damage to the tapes, but there is no electrical damage, because the effect of the bending of the paper is simply to produce slight spaces between successive layers of the paper tape. The amount of this separation is generally less than the separation that exists between alternate tape

layers at the butt spaces of the intervening tape.

A very great holding power is obtainable with applicant's strip grip clamping arrangement without damage to the conductor insulation. Tests have been made in which the strip grips were forced together over an insulated conductor joint by the ring clamps with a force of 250 pound per inch length, and subsequently, with the thrust still applied, electrical tests on the joint resulted in failure of the cable rather than in the joint. Subsequently, the thrust against the strips was relaxed to 200 per inch length and tensile tests were then made. The insulated conductor was cut off beyond the joint at both ends and one end of the cable was placed in one pair of jaws of the tensile machine and the assembly of strip grips was attached through a holding member to the other pair of jaws in the testing machine. Under these conditions and with strip grips approximately 54 inches long, a force of 8,500 pounds was required to slide the strips with respect to the conductor of the cable.

After, or in some cases before, the strip grips have been clamped against the conductor insulation they will be anchored relative to the cable pipe or to the joint casing to insure that there will be no movement of the conductor relative to the pipe. Conveniently this may be done by connecting the ends of the strip grips in one end of the joint casing by bolts 33 to studs 34 which are secured in the barrier plate 18. It is sufficient to hold the conductors if the strip grips are anchored at only one end.

Applicant has provided means for firmly gripping and anchoring insulated conductors relative to the pipe in which they are loosely enclosed without damage to the insulation. It will be evident that the strip grips and the associated clamps which press the strip grips against the conductor insulation constitute a clamping means which grips the insulated conductor. The conductors will be held against all forces which may develop therein tending to move them during operation of the cable.

The invention as herein described may be variously modified and embodied within the scope of the subjoined claims.

I claim:

1. In a cable system of the type in which insulated conductors are loosely enclosed by a pipe which is filled with an insulating fluid under pressure, in combination, two lengths of insulated conductor connected together in end to end relation with a body of insulation built up over the conductor connection to larger diameter than the original cable insulation and extending in both directions over the ends of the original insulation on the connected conductors, the end portions of the built-up insulation tapering down to the original conductor insulation, a plurality of strips extending longitudinally of the insulated conductor joint and spaced circumferentially therearound, clamping means engaging the strips and pressing them firmly against the insulated conductor joint whereby the strips grip the insulated conductor joint along narrow zones spaced circumferentially around the joint, said strips embracing the central built-up portion of the insulation and extending beyond the ends thereof over the tapered portions of the insulation, wedge shaped insulating pieces under the ends of the strips and held thereby in place against the tapered end portions of the built-up insulation, and means anchoring the strips to the enclosing pipe to prevent movement of the

insulated conductors relative to the pipe at the place of connection.

2. In a cable system of the type in which insulated conductors are loosely enclosed by a pipe which is filled with an insulating fluid under pressure, in combination, two lengths of insulated conductor connected together in end to end relation with a body of insulation covering the conductor connection, clamping means comprising a plurality of longitudinal strips spaced circumferentially around the insulated conductor connection, the said strips gripping the insulated conductor joint firmly along narrow zones spaced circumferentially around the joint, and means anchoring the strips to the enclosing pipe to prevent movement of the insulated conductors relative to the pipe at the place of connection.

3. In a cable system of the type in which insulated conductors are loosely enclosed by a pipe which is filled with an insulating fluid under pressure, in combination, means for preventing movement of an insulated conductor relative to the enclosing pipe comprising clamping means including a plurality of longitudinal strips, the said strips gripping the insulated conductor along narrow zones spaced circumferentially around the conductor, and means anchoring the strips against movement relative to the pipe.

4. A cable system as described in claim 3, in which the longitudinal strips are spaced circumferentially around the insulated conductor, and in which there are a plurality of cooperating clamps spaced longitudinally along the conductor exteriorly of the strips, the said clamps holding the strips pressed firmly and resiliently against the insulated conductor.

5. A cable system as described in claim 3, in which the longitudinal strips are spaced circumferentially around the insulated conductor, and in which there are a plurality of cooperating ring clamps spaced longitudinally along the conductor enclosing the strips, and radially disposed set screws in said ring clamps bearing against at least some of said strips, the said ring clamps and their set screws holding the strips pressed firmly and resiliently against the insulated conductor.

6. A cable system as described in claim 3, in which the longitudinal strips are of non-magnetic, metallic material and are spaced circumferentially around the insulated conductor, and in which there are a plurality of clamps spaced longitudinally along the conductor pressing the strips firmly against the insulated conductor, and in which the strips are individually covered with thin layers of insulating material.

7. A cable system as described in claim 3, in which the longitudinal strips are spaced circumferentially around the insulated conductor, and in which the clamping means includes a plurality of cooperating clamps spaced longitudinally along the conductor exteriorly of the strips to hold the strips pressed firmly and resiliently against the insulated conductor, characterized by the fact that the width of a strip is less than the spacing between strips and not more than about one third the length of the strip.

8. In a cable system of the type in which paper insulated cables are loosely enclosed by a pipe which is filled with an insulating fluid under pressure, in combination, a semi-stop to restrict flow of fluid longitudinally in the pipe, said semi-stop comprising a barrier plate extending across the pipe and having its edge in fluid tight sealing association with the wall of the pipe, an opening in the barrier plate through which passes

an insulated conductor, a packing gland surrounding the insulated conductor adjacent the barrier plate, means associated with the barrier plate to compress the packing gland against the barrier plate and about the insulated conductor substantially uniformly around its circumference, thus preventing flow of insulating fluid through the opening in the barrier plate around the insulated conductor and substantially restricting flow of insulating fluid longitudinally through the conductor insulation, clamping means comprising a plurality of longitudinal strips firmly gripping the insulated conductor adjacent the barrier plate in narrow zones spaced circumferentially around the conductor, and means anchoring the said clamping means to the barrier plate to prevent movement of the cable conductor relative to the packing gland and barrier plate.

20. 9. A semi-stop joint for cables of the type in which an insulated conductor is loosely enclosed by a pipe filled with an insulating fluid under pressure comprising, in combination, a joint casing connecting two pipe lengths, a barrier plate within the joint casing near one end thereof and connected adjacent its edge in fluid tight relation to the end of one of the pipe lengths, an opening in the barrier plate through which passes the end of an insulated conductor lying within the pipe length, means sealing the opening around the insulated conductor and pressing against the conductor insulation around its circumference to restrict substantially the flow of insulating fluid through the opening in the barrier plate between the joint casing and the pipe length, a connector uniting the said conductor within the joint casing to the end of a conductor lying in the other pipe length, a body of insulation enclosing the connected conductor ends, clamping means comprising a plurality of longitudinal strips firmly gripping the insulated conductor which extends through the barrier plate in narrow zones spaced circumferentially around the conductor, and means anchoring the clamping means to the barrier plate to prevent movement of the insulated conductor where it passes through the barrier plate.

10. A semi-stop joint according to claim 9, in which a second barrier plate similar to the first one is disposed within the joint casing near the other end thereof for restricting substantially the flow of insulating fluid between the joint casing and the said other pipe length.

11. A semi-stop joint according to claim 9 in which the longitudinal strips extend lengthwise of the conductor joint and are spaced circumferentially therearound, and in which the clamping means includes a plurality of ring clamps enclosing the conductor joint over the strips, said ring clamps having radially disposed set screws bearing against at least some of the strips so that the pressure of the latter against the body of insulation may be adjusted.

12. A semi-stop joint according to claim 9, in which the longitudinal strips are of metal and extend lengthwise of the conductor joint, spaced circumferentially therearound, and in which the clamping means includes a plurality of metal clamps holding the strips pressed against the insulation, and in which a thin layer of electrical insulation separates each strip from the clamps.

13. A semi-stop joint for oil-impregnated, paper insulated cables loosely enclosed within a pipe filled with an insulating fluid under pressure com-

11

prising, in combination, a joint casing connecting two pipe lengths, an insulated joint within said joint casing connecting an insulated conductor in one pipe length to an insulated conductor in the other pipe length, barrier means adjacent one end of the joint casing compressing the conductor insulation against the conductor around its circumference and substantially restricting flow of the insulating fluid between the joint casing and one of the pipe lengths, clamping means comprising a plurality of longitudinal strips firmly gripping the insulated joint throughout a majority of its length in narrow zones spaced circumferentially around the joint, and means rigidly connecting the clamping means to the barrier means to prevent movement of the insulated conductor relative to the barrier means.

14. In a cable system of the type in which insulated conductors are loosely enclosed by a pipe which is filled with an insulating fluid under pressure, in combination, means for preventing movement of an insulated conductor relative to the pipe comprising clamping means anchored to the pipe and gripping the insulated conductor, said clamping means comprising a plurality of strip grips extending lengthwise of the conductor and spaced circumferentially therearound, a plurality of ring clamps enclosing the conductor over the strip grips, and radially disposed set screws in said ring clamps bearing against at least some of the strip grips to press them against the insulated conductor, said ring clamps being substantially circular in form and sufficiently elastic so that upon tightening the set screws an increase in diameter of the ring clamps along the axis of the set screws up to about three percent is possible without permanent distortion of the ring clamps.

15. A semi-stop joint for oil-impregnated paper insulated cables loosely enclosed within a pipe filled with an insulating fluid under pressure

12

comprising, in combination, a joint casing connecting two pipe lengths, an insulated joint within said joint casing connecting an insulated conductor in one pipe length to an insulated conductor in the other pipe length, a barrier plate within said joint casing across the end of one pipe length, the edge of the barrier plate being in fluid tight sealing association with the end of the pipe, an opening in the barrier plate through which passes the end of an insulated conductor contained within the associated pipe, packing means associated with said opening and exerting pressure radially inwardly on the insulated conductor substantially uniformly around its circumference, said pressure being sufficient to restrict substantially the flow of insulating fluid through the opening in the barrier plate, but insufficient to crease the paper insulation enough to produce material damage to the insulation or to hold the conductor against longitudinal movement under the influence of forces which may be exerted thereon in the normal operation of the cable, clamping means comprising a plurality of longitudinal strips firmly gripping the insulated conductor adjacent the barrier plate, and means rigidly connecting the clamping means to the barrier plate to hold the conductor against movement relative to the barrier plate.
